(57) **CLAIM**

The ornamental design for a combined trash can and leaf
press with scooped rear edge, as shown and described.

DESCRIPTION

FIG. 1 is a right elevation view of a combined trash can and leaf
press with scooped rear edge showing our new design
with the lid and press removed for clarity, the opposite side
being a mirror image of the shown;

FIG. 2 is a front elevation view thereof;

FIG. 3 is a rear elevation view thereof;

FIG. 4 is a top plan view thereof;

FIG. 5 is a bottom plan view thereof; and,

FIG. 6 is an isometric view thereof.

1 Claim, 6 Drawing Sheets
